UNITED STATES PATENT OFFICE.

WILLIAM G. TAYLOR, OF HULTON, ASSIGNOR TO THE TAYLOR BURNER COMPANY, LIMITED, OF PITTSBURG, PENNSYLVANIA.

FUEL-GAS MIXER.

SPECIFICATION forming part of Letters Patent No. 497,435, dated May 16, 1893.

Application filed November 8, 1892. Serial No. 451,379. (No model.)

To all whom it may concern:

Be it known that I, WILLIAM G. TAYLOR, a citizen of the United States, residing at Hulton, in the county of Allegheny and State of Pennsylvania, have invented certain new and useful Improvements in Fuel-Gas Mixers, of which the following is a specification.

My invention relates to mixers for fuel gas, and my invention consists in constructing the said mixers as fully set forth hereinafter, so as to facilitate adjustment, secure a proper supply of oxygen, and maintain the fixed parts in their proper relations, all as fully set forth hereinafter, as illustrated in the accompanying drawings, in which—

Figure 1 is an external view of a gas mixer embodying my improvements; and, Fig. 2 is a longitudinal section thereof.

The nozzle or gas tip a^2 is connected with and preferably forms a part of a casting which includes a tube, A, having a lower flanged portion a which surrounds the nozzle a^2 and an upper hollow cylindrical portion b which is threaded exteriorly. The nozzle a^2 is connected with the flanged portion a of the tube through the medium of radiating arms or wings, 1, 1, of any suitable number sufficient to hold the parts in relative position and at the same time, to permit the entrance of the air into the lower mouth of the flanged portion. The nozzle a^2 is threaded for attachment to the supply pipe.

The threaded end b of the pipe A extends into the threaded end of a pipe d which is adapted to be connected with the burner or with the pipe leading to the burner in any suitable manner, and the said pipe d supports a cone f , which may be of any suitable material as steel, cast iron, porcelain or other refractory material, and which is supported by wings, 2, 2, extending to the sides of the tube d , sufficient in number to hold the cone in place and at the same time, permit the passage of the gases along the tube.

It has been found extremely desirable to adjust the cone f to and from the nozzle according to the character of the flow of the gas and to do this with extreme nicety without permitting the access of air except such as flows into the lower end of the flanged por-

tion a of the tube A, and in order to secure this result, I support the cone, f by the section d of the mixer and support the nozzle a^2 by the other section and connect the two sections together, as by the threaded connection, 51 so that one may be adjusted in respect to the other or turned in respect to the other to bring the cone nearer or carry it farther from the nozzle. This connection further enables me to bring the cone into very close proximity to the mouth of the nozzle which is sometimes quite important. It will be seen that whatever the adjustment may be, whether the cone is carried nearer to or farther from the nozzle, by the use of a screw connection 60 between the two tubes A and d , I am enabled to secure the desired connection without permitting the entrance of any air to the tube except such as flows in at the bottom.

In order to readily remove the cone f if it should be required either to replace it in consequence of wear or for other reasons, I prefer to provide it with a screw shank, 3, adapted to a threaded opening in the support, 2, to which it may be screwed and from which 75 it may be detached as desired. The nozzle a^2 may also be separate from the support, 1, and may be threaded so as to be connected to and detached from the latter, but I prefer to form the nozzle and the tube A in one piece 8c as before described, as it facilitates manufacture and insures absolutely the proper adjustment of the parts in relation to each other.

It will be seen that while I am thus enabled to adjust the relations of the nozzle a^2 85 and the cone f , I do not under any circumstances disturb the relation of the nozzle a^2 to the flanged portion a of the tube A, nor the relation of the cone f to the tube d .

Without limiting myself to the precise construction and arrangement of the parts shown, I claim as my invention and desire to secure by Letters Patent—

1. A mixer for fuel gas, comprising two tubes, one tube having a cylindrical portion, 95 a flanged portion and a nozzle, and the other comprising a cylindrical portion and a cone, the tubes being directly but adjustably connected together, so that the relation of the nozzle and cone may be adjusted without per- 100

mitting the access of air except through the lower end of the tube; substantially as described.

2. In a mixer for fuel gas, the combination with a tube, having a cylindrical portion, a flaring portion and a nozzle supported in the flaring portion near the mouth of the latter; of another tube having a cone centrally supported therein, the two tubes being directly 10 but adjustably connected together to move one within the other; substantially as described.
3. In a mixer for fuel gas, the combination with the tube A having a threaded portion, a flaring portion and a nozzle; of a tube d having a threaded portion adapted to engage the threaded portion of the tube A, and a cone supported in said tube d; substantially as described.
- 20 4. In a mixer for fuel gas, the combination with the tube having a cylindrical portion, a flaring portion, radial arms connected to said

flaring portion, and a nozzle supported thereby and formed integral with the tube; of another tube having a cylindrical portion embracing the cylindrical portion of the first tube, and having arms and a cone supported by said arms; substantially as described. 25

5. In a mixer for fuel gas, the combination with a tube A having a screw-threaded portion b, the flanged portion a and nozzle a² mounted therein; of a tube d having a screw-threaded portion fitting the portion b and provided with arms 2, and a cone f having a screw-threaded stem fitting a threaded socket 35 in said arms; substantially as described.

In testimony whereof I have signed my name to this specification in the presence of two subscribing witnesses.

WILLIAM G. TAYLOR.
